UNITED STATES PATENT OFFICE.

JOHN B. AUFULDISH, OF DAYTON, OHIO.

STARTER FOR EXPLOSIVE-ENGINES.

1,151,987.

Specification of Letters Patent.

Patented Aug. 31, 1915.

Application filed February 3, 1912. Serial No. 675,137.

To all whom it may concern:

Be it known that I, JOHN B. AUFULDISH, citizen of the United States, residing at Dayton, in the county of Montgomery and State of Ohio, have invented certain new and useful Improvements in Starters for Explosive-Engines, of which the following is a specification, reference being had thereto in the accompanying drawing.

10 This invention relates to starters for explosive engines and is designed more particularly for use in connection with automobile engines.

15 The object of the invention is to provide a starter which will be simple and inexpensive in construction and which will be simple and positive in operation.

20 It is also an object of the invention to provide means to maintain at all times a charge of explosive gas in storage near the engine cylinders from whence it may pass quickly into the cylinders.

25 To accomplish these objects it is a further object of the invention to provide a storage receptacle and means actuated by a push rod to connect said receptacle with either the source of gas supply or with the cylinders of said engine.

30 In the accompanying drawings, Figure 1 is a plan view of one form of starter embodying my invention; Fig. 2 is a section taken centrally through the device of Fig. 1; Fig. 3 is an end elevation of the same; Fig. 4 is a section taken on the line *b b* of Fig. 2 and looking in the direction of the arrows; Fig. 5 is a section taken on the line *a a* of Fig. 2 and looking in the direction of the arrows; Fig. 6 is a plan view of a modified form of the invention; Fig. 7 is, 35 a section taken centrally through the form of the device shown in Fig. 6; Fig. 8 is an end elevation of the device shown in Fig. 6; and Fig. 9 is a detail of a modified form of actuating device.

40 In these drawings I have illustrated two forms of starter in which the invention is embodied in substantially the same form, the devices differing in detail only.

45 In Figs. 1 to 5, inclusive, I have shown the invention embodied in a starter comprising a cylindrical casing 1 adapted to be secured to the dashboard 2 of an automobile or other suitable support and preferably having its greatest length extending parallel 50 with said dashboard or support. This cylinder comprises a receptacle for each cylin-

der of the engine, which receptacles are adapted to be connected with a source of gas supply and to receive and store charges of an explosive gas, each of which charges is sufficient when injected into a cylinder of an engine and exploded therein to impart movement to the piston in such cylinder and thus turn over the engine and cause charges of gas to be drawn into the other cylinders and the engine to operate in the usual manner. The connection between the storage receptacle or receptacles and the several cylinders of the engine is controlled by a reciprocating member, such as a push-rod, the movement of which in one direction will establish the connection between the receptacles and the respective cylinders and the movement of which in the opposite direction will connect the receptacles with the source of gas supply. One form of the device also comprises a series of secondary storage receptacles, preferably one for each cylinder of the engine, which receptacles are interposed between the source of gas supply and the first mentioned storage receptacles, which are connected with the engine cylinders. These secondary receptacles are in communication with the respective first-mentioned receptacles when the latter are cut off from the engine and are disconnected from the first-mentioned receptacles when these are in communication with the engine. Consequently, there are always two charges of gas for each cylinder supported close to the engine whence they can be quickly injected into the same.

55 In the present construction of the starter the casing 1 has in one end thereof a recess to receive a receptacle 4 which is divided into four chambers, indicated at 5. The several chambers of the receptacle 4 are adapted to communicate with the source of gas supply in a manner hereinafter to be described and each has a port 6 adapted to register with a corresponding port 7 in the wall of the casing and by moving the receptacle 4 in the recess the ports 6 can be moved into and out of alignment with the ports 7 in the casing, which latter ports are connected by means of conduits or tubes 8 with the respective cylinders of an explosive engine. Any suitable means may be provided for moving the receptacle 4 in its recess, but, as here shown, this receptacle constitutes a valve member, both the receptacle and the walls of the recess being ground to form a

snug fit and the receptacle is rotated in the recess or valve seat to establish communication between the chambers thereof and the respective cylinders of the engine. 5
movement may be imparted to the casing by any suitable means, but preferably this means is mounted upon the dashboard or supporting structure 2, and, in order to simplify the mechanism as much as possible 10 and at the same time insure a pause in the movement of the valve member sufficient to permit the gas to pass from the chambers to the cylinder, I prefer to provide a reciprocatory member, such as a push-rod 9, which 15 is slidably mounted in the dash 2 and operatively connected with the receptacle or valve member. When this rod is at one extremity of its movement the chambers will be connected with the cylinders, and, in order 20 to disconnect the chambers, it is only necessary to move the valve in the opposite direction. The slight pause which must necessarily occur during the reversal of movement of the rod affords ample time for the gas 25 to pass to the cylinders and thus insures a charge of gas sufficient to explode and impart movement to the engine. Further, the push-rod movement is exceedingly simple and requires a minimum amount of mechanism 30 on the dash-board. With it two movements are necessary to start the engine. One is to actuate the push-rod to connect the storage chambers with the cylinders and the other to operate the switch to produce 35 the spark in the engine cylinder. The pistons of the several cylinders will be in such positions that a charge of gas will be retained and exploded in one of them, thus imparting movement to the piston of that 40 cylinder and starting the engine. It is not necessary that the storage chamber should be disconnected from the engine before the latter is started, as the usual check valves will be provided at the point of connection 45 of the conduits with the cylinders.

One very simple form of connection between the push-rod and the casing or valve member is a rack and gear. In the present instance the casing is provided with a stem 50 10 on which is mounted a mutilated gear 11 and the push-rod 9, is provided with a toothed portion 12, which portion is preferably formed integral with the rod itself and the teeth of which mesh with the teeth 55 of the mutilated gear 11. In Fig. 9 I have shown a modified form of connection between the push-rod 9 and the receptacle and in this connection the stem 10 of the receptacle is provided with a crank disk 13 which 60 is connected with the push-rod by means of a link or connecting rod 14. Either of these two methods of connection of any other suitable method of connection may be employed.

65 The several chambers of the receptacle

may be connected with the source of gas supply in any suitable manner but preferably I interpose between the chambers of the receptacle 4 and the source of gas supply a second storage receptacle. This storage 70 receptacle has a capacity equal to the capacity of the four chambers of the receptacle 4 and is preferably divided into four compartments, each of which communicates with the respective chamber of the receptacle 4. As here shown the secondary storage chamber is formed in the casing 1 and is divided by partitions 15 into four compartments 16. The secondary storage receptacle is separated from the recess 3 in which the 80 receptacle 4 is mounted by means of a partition or head 17 in which is formed a valve seat 18 and which is also provided at the base of the valve seat 18 with a series of ports 19 communicating with the respective 85 compartments of the storage chamber.

The receptacle 4 is provided at its inner end with an extension 20 having a tapered end adapted to fit into the valve seat 18 and having formed therein a series of ports 21 90 corresponding in number with the ports 19 and arranged to register with those ports when the casing 4 is in one position. A spring 22 is confined between a pin 23 mounted in the extension 20 and a washer 24 mounted on the extension 20 and engaging the edges of the casing 1 on opposite sides of the recess 3. This spring tends to hold both the extension 20 in engagement with the valve seat 18 and the receptacle 4 100 in contact with the walls of the recess 3. The ports 21 are so arranged with reference to the ports 6 that when the latter are in communication with the ports 7 in the casing the ports 21 will be out of alignment 105 with the ports 19. Consequently, the chambers of the receptacle 4 will be cut off from the source of gas supply and only the measured charge contained in each chamber will be admitted to the engine. If desired the 110 communication between the secondary storage receptacle and the source of supply may also be cut off while the chambers 4 are in communication with the engine, thus providing a double cut-off between these chambers and the source of supply. In the present instance that end of the casing 1 adjacent to the secondary chamber is closed by a cap 115 screw-threaded into the end of the casing and spaced some distance away from the 120 ends of the partitions 15 and compartments 16, thus forming in this space a chamber 26 which communicates with the source of supply by means of a conduit 27 formed along the side of the casing 1 and connected with 125 a passageway or conduit 28 in a nipple 29. The passageway 28 of the nipple is arranged in alignment with the toothed portion of the push-rod and extends inward beyond the end of the conduit 27. The toothed portion 130

of the push-rod is provided with a plunger or piston 30 which fits snugly in the passage 28 and, when the push-rod is in its innermost position, will extend across the end 5 of the conduit 27 and close the same, thus cutting off the chamber 26 and the storage chamber from the source of supply. This source of supply may be of any suitable character and any suitable explosive gas or 10 vapor may be employed but the present device is designed especially for use with acetylene gas and the source of supply may be a generator or tank commonly known as a presto-lite tank, which tank may be carried 15 on any convenient part of the automobile, usually at a distance greatly removed from the engine. By interposing the storage chambers between the source of supply and the engine and arranging them close to the 20 engine there is always a charge of gas in a position from whence it will pass quickly to the cylinders without the delay incident to the travel of the gas from the source of supply through the long conduit to the engine and enabling the charge to be injected 25 in the engine by a very brief pause in the movement of the operating device and avoiding any possibility of this device being operated so quickly as to prevent proper 30 charges entering the cylinders. Further, these chambers insure not only a sufficient charge but also that the charge will not be too great as might readily result if the operator were required to gage the length of 35 time the source of supply was connected with the cylinders. If the secondary chamber is eliminated and the chambers 4 connected directly with the chamber 26 by means of suitable valves, such as are shown, 40 there would remain all the advantages above recited but by utilizing the secondary storage chamber I have two charges of gas close to the engine and it is possible to inject these 45 charges in the engine in rapid succession should the engine fail to start on the first charge, either because of the lack of the 50 proper supply of gas from the carburetor or the failure of the spark, or any other reason. It will be noted that when the push-rod 55 is in its outermost position both the primary and secondary storage chambers will be in communication with the source of gas supply and will be cut off from the cylinder. When the push-rod is in its innermost position 60 the primary storage chambers will be connected with the respective cylinders of the engine and will be cut off from the secondary cylinders and these latter will also be cut off from the source of supply but will 65 contain charges of gas ample to again supply the primary chambers. Consequently, if the operator fails to disconnect the primary cylinders from the engine and shuts down his engine with the starter in this position he will still have ample gas in a position to be

readily injected into the engine and it will only be necessary to impart a complete reciprocation to the push-rod to inject these charges into the cylinder inasmuch as the pause required to reverse the movement of the push-rod will be ample for the gas to pass from the secondary to the primary chambers. If the primary chambers are disconnected from the engine prior to the time it is desired to again operate the starter the 70 operation would be the same as if the secondary chambers were omitted altogether. 75

The casing 1 may be constructed in any suitable manner but for convenience of manufacture and to permit of the ready access to the parts thereof I prefer to form the same in two parts, one containing the primary storage receptacle and the other containing the secondary storage chamber and constituting a storage receptacle separate from the first-mentioned storage receptacle. In the present instance the two parts of the casing are connected together by providing one part with internal screw threads and the other part with a screw-threaded flange to engage said screw- 85 threads, as indicated at 47.

In Figs. 6, 7 and 8 I have illustrated a slightly modified form of the invention. As here shown a casing 31 is secured to the 90 supporting structure in the same manner as is the casing 1 above described. This casing has a recess or valve seat 32 similar to the recess 3 and having mounted there- 95 in a receptacle 33 having a single chamber; 100 which chamber is normally in communication with the source of gas supply, preferably by means of a port 34 extending through one end of the receptacle and communicating with the chamber 33 in the cas- 105 ing 31, which chamber is connected by means of a conduit 36 with a source of supply. A receptacle 33 is provided with one or more ports 37 arranged to be moved into regis- 110 tration with one or more ports 38 formed in the casing 31 and connected with a cyl- 115 inder or cylinders of the engine by means of a conduit or conduits 39. The receptacle 33 is movable and by imparting proper movement thereto the port or ports there- 120 in can be caused to register with the port or ports in the casing leading to the cylinder of the engine. While the number of ports in the casing and in the receptacle may be varied according to circumstances 125 I prefer to provide the casing with a port for each cylinder and to provide the receptacle with a similar number of ports, which latter ports may be arranged either to reg- 130 ister simultaneously with the respective ports in the casing or to register successively with the several ports in the cas- ing. The exhaust valve or valves of one or more cylinders will always be open and any charge of gas injected into such cylinder or

cylinders will pass immediately to the atmosphere. Consequently, if the receptacle 33 is placed in communication simultaneously with all cylinders of the engine there will be a tendency for a large portion of the gas to pass through the cylinder or cylinders having the open exhaust to the atmosphere and thus preventing a proper charge from being injected in the cylinder the piston of which is in a position to permit of an explosion therein. I find the simplest way of overcoming this difficulty is to connect the receptacle successively with the several cylinders, allowing time in each instance for sufficient gas to pass from the receptacle to the cylinder to charge the latter, thereby dividing the gas in the receptacle equally or substantially so between the several cylinders, thus insuring that the cylinder which is in condition for an explosion will receive a proper charge. Motion may be imparted to the receptacle 33 in any suitable manner, preferably by means of a gear 40 and a push-rod 41 having a toothed portion, as above described. In this instance, however, it is essential that the communication between the engine and the source of supply should be interrupted and I have, therefore, provided means for automatically returning the receptacle to its normal position. This means, as here shown, comprises a spring 42 connected at one end with the rack 41 and at the other end with the supporting structure 2. A spring 43 coiled about an extension 44 on one end of the receptacle 33 and confined between a stop 45 on the outer end of the stem and a washer 46 resting against the casing on opposite sides of the recess 32 serves to hold the casing snugly in engagement with the walls of the recess.

While I have shown and described two forms in which the invention may be embodied it will be understood that these two forms were chosen for the purposes of illustration only and that I do not desire to be limited to the details of construction shown and described, for obvious modifications will occur to a person skilled in the art.

Having thus fully described my invention, what I claim as new and desire to secure by Letters Patent, is:

1. In a starter, a casing having a series of ports connected with the respective cylinders of an engine, a receptacle movably mounted in said casing and having ports adapted to register with the respective ports in said casing, and means for imparting movement to said receptacle to connect the ports therein with the corresponding ports in said casing.

2. In a starter, a casing having a plurality of ports connected with the respective cylinders of an engine, a receptacle movably

mounted in said casing and having a series of compartments each communicating with a source of gas supply and having ports adapted to register simultaneously with the respective ports in said casing, and means for imparting movement to said receptacle.

3. In a starter, a casing having a port connected with an engine, a receptacle movably mounted in said casing to receive and store a charge of gas, said receptacle communicating with a source of gas supply and having a port, a gear operatively connected with said movable receptacle, and a push-rod having a toothed portion meshing with said gear.

4. In a starter, a casing having a port connected with an engine, a receptacle movably mounted in said casing to receive and store a charge of gas, said receptacle communicating with a source of gas supply and having a port, and a push-rod operatively connected with said movable receptacle.

5. In a starter, a casing having a port connected with an engine, and a receptacle movably mounted in said casing to receive and store a charge of gas, said receptacle having a port adapted to register with the port in said casing and communicating with a source of gas supply, and means to impart movement to said receptacle and to control the length of time said ports are in register one with the other.

6. In a starter, a casing having a plurality of ports connected with the respective cylinders of an engine, a receptacle movably mounted in said casing and having a plurality of ports adapted to register with the respective ports in said casing, and means to impart movement to said receptacle and to control the length of time the ports of said receptacle shall remain in register with the ports of said casing.

7. In a starter, a casing having a recess therein, a port connecting said recess with an engine, a receptacle rotatably mounted in said recess to receive and store a charge of gas and having a port to register with the port in said casing, and means for rotating said receptacle.

8. In a starter, a casing having a recess therein, a port connecting said recess with an engine, a receptacle rotatably mounted in said recess to receive and store a charge of gas and having a port to register with the port in said casing, a gear connected to said receptacle, and a push-rod having a toothed portion meshing with said gear.

9. In a starter, a casing having a recess therein and having a series of ports connecting said recess with the respective cylinders of an engine, a receptacle rotatably mounted in said recess and divided into a plurality of compartments and each compartment having a port adapted to register

- with the corresponding port in said casing, and means for actuating said receptacle to cause the ports therein to register with the ports in said casing.
5. 10. In a starter, a casing having a recess therein and having a series of ports connecting said recess with the respective cylinders of an engine, a receptacle rotatably mounted in said recess and divided into a plurality of compartments and each compartment having a port adapted to register with the corresponding port in said casing, and a rack and gear mechanism connected with said receptacle to rotate the same and cause the ports therein to register with the ports in said casing.
10. 11. In a starter, a distributor comprising two storage receptacles communicating with each other and with a source of gas supply, and means for connecting one of said receptacles with a cylinder of an engine.
15. 12. In a starter, two receptacles, conduits to connect one of said receptacles with the cylinder of an engine and to connect the other of said receptacles with a source of gas supply, and means for establishing communication between said receptacles and for interrupting said communication and connecting the first-mentioned receptacle with the cylinder of said engine.
20. 13. In a starter, a casing having two storage chambers, a conduit to connect one of said storage chambers with a cylinder of an engine and to connect another of said chambers with a source of gas supply, said casing having ports to connect said chambers one to the other, and operable means to connect the first-mentioned chamber with the conduit leading to said engine and to close said ports to disconnect said first-mentioned chamber from the last-mentioned chamber.
25. 14. In a starter, a casing having recesses near the opposite ends thereof, each recess constituting a storage chamber, said casing also having ports leading from one of said recesses to the cylinders of an engine, a port connecting the other of said recesses with a source of gas supply, and ports to connect said recesses one with the other, a rotary member mounted in that recess which is connected with the engine and having ports to register with the ports leading to said engine and having other ports to register with the ports leading to the other chamber, and
30. 15. means for moving said receptacle to place the same in communication with the engine and disconnect the same from the other chamber.
35. 16. In a starter, a casing having recesses near the opposite ends thereof, each recess constituting a storage chamber, said casing also having ports leading from one of said recesses to the cylinders of an engine, a port connecting the other of said recesses with a source of gas supply, and ports to connect said recesses one with the other, a rotary receptacle mounted in that chamber having ports leading to said engine and having a plurality of compartments corresponding in number with the ports leading to said engine and having ports to register with the ports leading to said engine, each of said compartments also having a port to communicate with the ports leading to the chamber which is connected with the source of gas supply, and means to rotate said receptacle to control the positions of the ports therein.
40. 17. In a starter, a casing having two recesses therein, one of said recesses communicating with a source of gas supply and having a series of compartments, each compartment having a port, the other of said recesses having a series of ports leading to the cylinders of an engine, a receptacle rotatably mounted in the last-mentioned recess having a series of compartments corresponding in number to the compartments in the first-mentioned recess and having ports to register with the ports leading to said engine and having other ports to register with the ports of the compartments of the first-mentioned chamber, and means to rotate said receptacle.
45. 18. In a starter, a casing having two recesses, a conduit connecting one of said recesses with a source of supply, a cut-off for said conduit, said casing having a port connecting the other of said recesses with a cylinder of an engine and another port connecting said last-mentioned recess with the first-mentioned recess, and operable means for simultaneously controlling the ports of said last-mentioned recess and the cut-off for said conduit.
50. 19. In testimony whereof, I affix my signature in presence of two witnesses.

JOHN B. AUFULDISH.
